Primary Examiner—Paula Greene

(74) *Attorney, Agent, or Firm*—Lackenbach Siegel, LLP

(57) **CLAIM**

The ornamental design for a jewelry attachment member, as shown and described.

DESCRIPTION

FIG. 1 is a front perspective view of a jewelry attachment member showing our new design.

FIG. 2 is a front perspective view of the embodiment shown in FIG. 1.

FIG. 3 is a front plan view of the embodiment shown in FIG. 1.

FIG. 4 is a back plan view of the embodiment shown in FIG. 1.

FIG. 5 is a right hand side plan view of the embodiment in FIG. 1, the left hand side being a mirror image.

FIG. 6 is a top plan view of the embodiment in FIG. 1.

FIG. 7 is a bottom plan view of the embodiment in FIG. 1.

FIG. 8 is a front perspective view of a second embodiment of a jewelry attachment member showing our new design.

FIG. 9 is a front perspective view of the embodiment shown in FIG. 8.

FIG. 10 is a front plan view of the embodiment shown in FIG. 8.

FIG. 11 is a back plan view of the embodiment shown in FIG. 8.

FIG. 12 is a right hand side plan view of the embodiment in FIG. 8, the left hand side being a mirror image.

FIG. 13 is a top plan view of the embodiment in FIG. 8.

FIG. 14 is a bottom plan view of the embodiment in FIG. 8.

FIG. 15 is a front perspective view of a third embodiment of a jewelry attachment member showing our new design.

FIG. 16 is a front perspective view thereof.

FIG. 17 is a front plan view thereof.

FIG. 18 is a back plan view thereof.

FIG. 19 is a right hand side view thereof, the left hand side is a mirror image.

FIG. 20 is a top plan view thereof; and,

FIG. 21 is a bottom plan view thereof.

The broken lines in FIGS. 1, 2, 3, 5, 8, 9, 10, 12, 15, 16, 17, and 19 form no part of the claimed design.
